[57] CLAIM

The ornamental design for a combined flare carrier and flare igniter, as shown and described.

DESCRIPTION

FIG. 1 is a perspective view of a combined flare carrier and flare igniter showing our new design;
FIG. 2 is a front elevational view thereof;
FIG. 3 is a rear elevational view thereof;
FIG. 4 is a left side elevational view thereof;
FIG. 5 is a top plan view thereof;
FIG. 6 is a right side elevational view thereof;
FIG. 7 is a bottom plan view thereof;
FIG. 8 is a perspective view of a second embodiment thereof;
FIG. 9 is a front elevational view thereof;
FIG. 10 is a rear elevational view thereof;
FIG. 11 is a left side elevational view thereof;
FIG. 12 is a top plan view thereof;
FIG. 13 is a right side elevational view thereof; and,
FIG. 14 is a bottom plan view thereof.
